UNITED STATES PATENT OFFICE.

WILLIAM J. MEINEL, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DEVICE FOR FILING OR ABRADING.

Application filed June 19, 1922. Serial No. 569,313.

My invention relates to an improved device for filing or abrading.

The chief object of my invention is to provide an abrading or filing device which is simple in structure and efficient in operation, and which, in operation, is effective in removing a considerable amount of material from the work at each working stroke.

A further object of my invention is to provide an abrading or filing device in which the file or abrading tool is automatically removed from contact with the work, when the device is moved in one direction, so that the file acts on the work in one direction only.

Further objects, and objects relating to details and economies of operation and construction, will definitely appear from the detailed description to follow. In one instance, I accomplish the objects of my invention by the devices and means described in the following specification. My invention is clearly defined and pointed out in the appended claims. A structure constituting a preferred embodiment of my invention is illustrated in the accompanying drawing, forming a part of this specification, in which:

Fig. 1 is a view of the device in side elevation.

Fig. 2 is a plan view of the same.

Fig. 3 is an enlarged, fragmentary sectional view, taken on line 3—3 of Fig. 2, and

Fig. 4 is a view similar to Fig. 3 but showing the file removed from contact with the work.

In the drawing, the same reference numerals refer to the same parts throughout the several views, and the sectional views are taken looking in the direction of the arrows at the ends of the section lines.

In the metal working art it frequently becomes necessary to reduce or file down surfaces of the work. For example, in making large dies it is a common practice to file down the surface of the die. This work, heretofore, has been accomplished, largely, by the manual application and manipulation of hand files, and, consequently, has been slow and tedious, thereby adding to the cost of making the die, besides imposing considerable physical labor on the workmen. It is among the special purposes of my present invention to provide an abrading or filing device of simple structure whereby

this work may be accomplished expeditiously and easily, the cost thereof reduced, and the workmen largely relieved of the physical and tedious toil. In carrying out my invention, I purpose to provide an abrading or filing device wherein the abrading tool or file is moved back and forth over the surface to be reduced and is automatically raised from or lowered into contact with the surface of the work according to the direction of movement of the device, the back and forth movements of the device being utilized to effect the automatic raising and lowering of the abrading tool or file, whereby the tool or file becomes effective in performing its work only when the device moves in one direction, and is withdrawn from working position when the device is moved in the opposite direction.

My invention is capable of being carried out in many and various practical embodiments.

In the accompanying drawing I have shown one illustrative practical form of device embodying my invention. The work or piece to be filed down is indicated at 10, over or upon the surface of which the abrading tool or file, 11, is adapted to be moved back and forth. This tool is carried by a suitable holder or carrier, 12, to which it is secured in any suitable or convenient manner, as for example by means of clamp devices, 13, in such relation as permits its abrading or file surface to be presented towards the surface of the work. The holder or carrier, 12, is provided, at the ends thereof, with handles, 14, by which it is moved back and forth over the work. The holder or carrier, 12, is supported by supporting members, shown in this instance as wheels, 17, which rest upon the surface of the work. In the particular arrangement shown, to which, however, my invention is not to be limited, the supporting members, 17, are employed in pairs, the members of which are respectively disposed at opposite sides of the holder or carrier, 12, and are carried by spindles, 16. The holder or carrier, 12, is provided with transverse slots or openings, 15, which are inclined in the direction of the length of the holder or carrier, 12. The spindles, 16, extend through these slots or openings.

With a structure such as above described, it will be seen that when force is applied

through one or both of the handles, 14, or otherwise, to move the file in the direction of its length over the surface of the work, there is an initial tendency for the holder or carrier, 12, to move or shift relatively to the spindles, 16. If this initial relative movement is in one direction, say towards the right, as indicated by the arrow in Fig. 3, the spindles will tend to occupy the higher portions of the inclined slots, 15, and, hence, a downward movement is imparted to the holder or carrier to cause the abrading or filing surface of the tool, 11, to be brought and constantly pressed towards and into contact with the surface of the work to perform its abrading or filing function. The greater the extent of the relative longitudinal movement of the holder or carrier the greater will be the relative lowering movement of the holder and, hence, of the working surface of the tool upon or towards the work surface. On the other hand, if the initial relative longitudinal movement of the holder is in the opposite direction, the spindles, 16, will tend to occupy the lower portions of the slots or openings, 15, as indicated in Fig. 4 and hence the holder or carrier and the abrading tool or file are raised from the surface of the work. Thus it will be seen that, in the working stroke of the device, the abrading tool or file is automatically lowered onto and constantly pressed towards the surface of the work, and, in the reverse movement of the device, the tool is automatically raised from the work surface, the back and forth movements of the device serving to effect the automatic lowering and raising of the tool upon and from the surface of the work. It is important, in the proper use of a file, that the file contact with the work only on the working stroke and be lifted out of contact with the work on the return stroke. In the use of the hand files heretofore employed, it is necessary for the workman to lift the file from the work and hold it away from the work during the return stroke but, with a device embodying my invention, the workmen simply pull and push the device back and forth and this back and forth movement automatically raises and lowers the file, thus reducing the labor required. Furthermore, on the working stroke, the tendency is to press the file surface constantly down upon the work, thus accomplishing the filing operation effectively and expeditiously and reducing the time required and, hence, the cost. This device is particularly useful in working on large surfaces. For instance, I have found it particularly advantageous in filing down the surfaces of large dies. Two men can use the device and, with it, remove the metal a great deal more speedily and

easily than if they worked separately with the smaller files heretofore used. This device, therefore, has enabled me to lower the cost of die construction materially.

The particular apparatus illustrated in the drawing may be varied considerably without departing from the spirit of my invention, and, therefore, I claim my invention broadly, as indicated by the appended claims.

Having thus described my invention, what I claim as new and useful and desire to secure by Letters Patent is:

1. A device of the kind described comprising a file, a carrier to which the file is secured, and carrying wheels running on the work and supporting the file and carrier and provided with journal pins, said carrier having inclined surfaces engaging said pins whereby relative movement between said pins and carrier raises and lowers the file and carrier with respect to the work.

2. A device of the kind described comprising a file, a carrier to which the file is secured, said carrier having openings therethrough, each with an inclined edge, journal pins extending through said openings and engaging said inclined edges, and carrying wheels mounted on said pins and running on the work.

3. A device of the kind described comprising a carrier having a plurality of openings therethrough, each of said openings having an inclined upper edge, journal pins extending through said openings and engaging the inclined upper edges thereof, a plurality of pairs of supporting wheels mounted on said pins and rolling on the work, and a file secured to the surface of the carrier adjacent the work.

4. A device of the kind described comprising a carrier, means for supporting a carrier upon the work, means for moving said carrier back and forth on the work, a file carried by said carrier, and means independent of said moving means whereby the back and forth movements of the carrier automatically raise and lower the file from and upon the work.

5. A device of the kind described comprising a file, a carrier therefor, means for moving the carrier back and forth, wheels running upon the work and supporting the file and carrier, and means independent of said moving means and interposed between the wheels and the carrier whereby the back and forth movements of the carrier automatically raise and lower the file from and upon the work.

In testimony whereof, I affix my signature.

WILLIAM J. MEINEI.
